US0D1059297S

(12) **United States Design Patent** (10) **Patent No.:** **US D1,059,297 S**
(45) **Date of Patent:** **** Jan. 28, 2025**

(54) **CIRCUIT BREAKER**

(71) Applicant: **Jiangsu Barep Smart Technology Co., Ltd**, Zhangjiagang (CN)

(72) Inventors: **Jiangang Chen**, Zhangjiagang (CN); **Xiaobo Zheng**, Zhangjiagang (CN)

(73) Assignee: **Jiangsu Barep Smart Technology Co., Ltd**

(**) Term: **15 Years**

(21) Appl. No.: **29/883,008**

(22) Filed: **Jan. 23, 2023**

(30) **Foreign Application Priority Data**

Dec. 23, 2022 (CN) 202230857702.7

(51) **LOC (15) Cl.** **13-03**

(52) **U.S. Cl.**

USPC **D13/137.3**; D13/160

(57) **CLAIM**

The ornamental design for a circuit breaker, as shown and described.

DESCRIPTION

FIG. 1 is a first perspective view of a circuit breaker showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the circuit breaker that form no part of the claimed design.

1 Claim, 8 Drawing Sheets
